UNITED STATES PATENT OFFICE

2,438,697

KNITTING MACHINE

Oscar Fregeolle, Central Falls, R. I., assignor to
Hemphill Company, Central Falls, R. I., a corporation of Massachusetts

Original application October 18, 1944, Serial No.
559,136. Divided and this application September 12, 1945, Serial No. 615,808

3 Claims. (Cl. 66—135)

1

This is a division of application for United States Letters Patent No. 559,136, filed October 18, 1944. In the application referred to there is disclosed, among other things, a novel type of wrapping head peculiarly suited for use in circular knitting machines having coaxial superposed needle cylinders. There is also disclosed a novel form of toe pocket spreader and fabric take-up for applying tension to the fabric during knitting. These are shown in connection with a two cylinder machine of the above type but may be used as well in single cylinder machines. This application is concerned with these things.

In the drawings:

Fig. 1 is a general view of the mechanism for producing wrap patterns and also of the means for applying tension to the fabric through the heel and toe pocket;

Fig. 2 is a view illustrating particularly the heel and toe pocket spreader and the device for applying tension to the fabric immediately following these parts independently of the regular fabric tension;

Fig. 3 is an elevation partly in section illustrating this tensioning device and also showing the position of the wrap spindle with respect to it and to the cylinders;

Fig. 4 is a general illustrative view of the machine;

Fig. 5 is a view of a part of the means for operating the wrap mechanism;

Fig. 6 is a view primarily illustrating the means through which these parts and the heel and toe pocket spreader are operated;

Fig. 7 is a view of the two cylindrical driving shafts for the two wrap heads shown in Fig. 1;

Figs. 8 and 9 are plan view of these two wrap heads;

Fig. 10 is a plan view showing the wrap spindle and the means by which the wrap mechanism is supported and moved into and out of operating position;

Fig. 11 is a similar elevation partly in section;

Fig. 12 is a plan view illustrating the lower cylinder, the position of the wrap horn and of one type of wrap spindle;

Fig. 13 is an elevation partly in section also illustrating the wrap horn;

Figs. 14, 15 and 16 are views illustrating the manner in which wrap and color-within-color wrap may be produced;

Figs. 17 and 18 are views illustrating another type of wrap head having frangible eyelets useful for producing the wrap patterns in the stocking of Fig. 19;

2

Fig. 19 illustrates part of a stocking in the leg of which there are alternating panels of rib and plain fabric with reverse plated patterns in the plain fabric panels, these patterns being outlined by wrap patterns produced by reverse spiral wrapping; and

Figs. 20, 21 and 22 are views of fragments of the wrap mechanism support illustrating particularly the means by which its movement may be adjusted.

As is well known, when stockings are knit as string work and particularly when rib knitting is being done, tension is maintained on the fabric to assist in the casting off of loops from the needles. Generally speaking, any suitable type of fabric take-up may be employed. However, the knitting of the heel and toe pockets introduces unsymmetrical portions of fabric which completely eliminate the possibility of uniform tension being applied to the fabric immediately succeeding them by the usual fabric take-up means. Consequently, a supplementary take-up device should be used to apply tension to the heel and toe pockets so that the immediately succeeding fabric may be properly tensioned at all points.

A form of supplementary take-up of this character is shown in Figs. 1, 2 and 3. It consists of a disc-like pocket spreader 81 mounted on the end of a rod 82 extending from the uppermost part of the machine through tubular shafts 83 and 84 within housing 85. Normally rod 81 is maintained in its uppermost position, that shown in Fig. 1, by a spring 86. In this position, spreader 81 is inoperative.

Associated therewith is the supplementary fabric take-up proper 87 (Figs. 2 and 3). This consists of a ring 88 longitudinally movable within the cylinder 1, provided with inwardly projecting needle-like points 89 adapted to engage with the fabric of the heel or toe pocket. Ring 88 is mounted on a rod 90 by which it is moved up and down by suitable mechanism. In spreader 81 are 40 V-shaped recesses 91 adapted to register with points 89 as shown in Fig. 2.

Registry is maintained through a pin 92 (Figs. 4, 5 and 6) mounted in a ring 93 (Figs. 4, 5, 6, 10 and 11) vertically slidable on housing 85 and 50 projecting through a slot in this housing so as to engage a recess 94 in rod 82. This recess is of sufficient length to permit rod 82 to move up and down the required distance but will prevent it from turning independently of housing 85. 55 Spreader 81 and supplementary take-up 87 ro-

tate with the cylinders, consequently, their relative positions in this respect are constant.

When the heel pocket is completed rod 82 is caused to move downward against spring 86 by suitably timed operating means, indicated in Fig. 1 by the lever 95, to engage spreader 81 with it. This spreads the pocket 96 substantially as shown in Fig. 3. Thereupon supplementary fabric take-up 87 moves up from a low position, passes along the outside of toe pocket 96 to substantially the position shown in Fig. 3, the points 89 penetrating the fabric of the toe pocket. Then spreader 81 is permitted to move upward again to its inoperative position and take-up 87 is released to descend of its own weight, supplemented by a spring, if desired, as the subsequent knitting progresses and maintaining tension upon the fabric above the toe pocket.

When the supplementary take-up has reached a low position it is released, the tension then being maintained by the regular fabric take-up. After the toe pocket is completed the same procedure is repeated to maintain tension on this side of the fabric subsequently knitted.

During both of these operations the rest of the fabric such as that of the leg passes through the arcuate slit 97 forming an extension of take-up 87 on the side opposite points 89. This fabric is tensioned throughout by the regular fabric take-up. Through the cooperation of the regular and auxiliary take-ups an adequately uniform tension is maintained on the fabric at all points to insure perfect knitting.

The pocket spreader 81 also serves to keep the heel pocket out of the way of the wrap heads and wrap yarns when they are in operation.

The auxiliary take-up just described is a modification of that shown in U. S. Patent #2,068,605 to which reference may be had for a more detailed description of its general characteristics and mode of operation. Except for the heel spreader 81 and its operating mechanism the take-up may be considered as substantially identical in construction and in operation to that of this patent. Attention is called to claims 3, 4 and 8 of the patent referred to which are believed to cover broadly the supplementary take-up of this invention.

The toe pocket spreader above described may be conveniently supported by the wrap mechanism now to be described. This mechanism is illustrated by Figs. 1-18, inclusive. It has wide possibilities including the making of the so-called reverse spiral wrap such as that shown in Fig. 19 outlining the reverse plated diamonds. As shown in Fig. 1 the machine is provided with two tubular shafts 83 and 84 rotatable within housing 85 terminating at their lower ends in disc-like heads 108 and 109, respectively. Shafts 83 and 84 are provided with spiral slots 110 and 111, respectively, one being the reverse of the other as shown in Fig. 7. Pin 92 on vertically slideable ring 93 passes through spiral slots 110 and 111. Therefore, by moving pin 92 up or down by means of ring 93 heads 108 and 109 can be made to rotate in both directions but always in opposite directions.

A wrap spindle of this type is suitable for producing the double spiral wrap outlines of the diamonds shown in Fig. 19. Its scope is, in fact, much greater than this. It can produce double spiral wrap patterns entirely around the stocking. The manner in which such a spindle oper-

ates is fully described in Patent #2,230,213 to which reference may be had.

The vertical movement of ring 93 just described is obtained by means of a pivoted yoke 112 (Figs. 4, 5, 6, 10 and 11) operated at the required times by suitable mechanism indicated by the rod 113 (Figs. 10 and 11). Housing 85 and, consequently, the wrap spindle are driven in a 1 x 1 relation to the cylinders through gears 114, 115, 116 and 117. When the wrap spindle which passes down through the upper cylinder as will be seen from Figs. 4, 10 and 11 is idle, it is substantially concentric with that cylinder.

When it is to operate to produce wrap patterns, it is swung into the eccentric position shown in Fig. 10 in which heads 108 and 109 are in the usual position overlapping the needle circle occupied by eccentric wrap spindles in single cylinder machines. This horizontal swinging of the wrap spindle is effected without disengaging it from gears 114-117. It simply swings in a concentric arc around gear 116. When swung into concentric position, obviously, its timing will be altered but it is then inoperative so that this is immaterial. When it is swung again into the eccentric operating position its timing is restored.

The means for swinging the wrap spindle in this way includes yoke 112 which besides being pivotally mounted for vertical movement, is also mounted on hub 118 swingably mounted on post 119 concentric with gear 116. Hub 118 is provided with arm 120 by means of which it is swung through suitable operating mechanism indicated by the lever 121 in Figs. 4, 10 and 11.

Gear 117 is rotatably and swingably supported by a plate 122 integral with or attached to hub 118 and resting in a fixed arcuate guide 123 (Figs. 1, 4, 10, 11, 20, 21 and 22). Guide 123 is provided at each end with adjusting screws 124 and 125, respectively, by means of which the concentric and eccentric positions of the wrap spindle can be adjusted.

In fact, plate 122 supports the entire wrap mechanism shown in Fig. 1 including the wrap spindle proper, the bobbin support 126, wrap yarn take-up mechanism 127 and, in addition, the heel and toe pocket spreader already described. All of these elements swing as a unit with plate 122.

A wrap horn such as that shown at 128 in Fig. 12 is provided for the usual purpose. This is supported upon a rod 129, Figs. 4, 10, 11, 12 and 13, extending through upper cylinder 2 and terminating in an offset bracket 130 (Figs. 4 and 11) connected to a short downwardly projecting shaft 131 which passes through a fixed sleeve 132. Shaft 131 is slideable in sleeve 132 but is prevented from turning by screw 133 passing through a slot 134 in the sleeve. Shaft 131 is urged downwardly by spring 135. When in its downward position horn 128 is in position to cooperate with the wrap spindle to produce wrap patterns. Shaft 131 and, consequently, rod 129 and wrap horn 128 can be moved upward by suitable mechanism operating against the end of shaft 131 indicated in Fig. 11 by the numeral 136 to move the wrap horn up out of the way at any time when wrapping is not being done.

Another wrap spindle of several which may be used for introducing wrap patterns in plain or plated panels such as that shown at 104 in Fig. 19 in an otherwise true rib stocking is illustrated by Figs. 17 and 18. Here, as before, there are two wrap heads 137 and 138 one smaller than the

other mounted in the same positions on tubular shafts 83 and 84, respectively. In this instance, however, the several eyelets or yarn guides 139 are at the extremities of frangible tongues 140 any number of which can be broken out, the construction suggesting that of the frangible butts on several well-known types of jacks. By breaking out all of these tongues with the exception of a few at opposite sides of each head the wrap spindle can be kept in wrapping position for making wrap patterns in the non-rib side panels of a stocking such as that shown in Fig. 19 without interfering with the needles when they operate in both cylinders to knit the true rib parts 105 alongside. If desired, double spiral wrap can be produced by this spindle, the two heads being shogged in opposite directions in the same way and by the same mechanism described above. For other types of wrapping one of the heads 137 or 138 can be used alone.

I claim:

1. In a knitting machine having superposed, axially aligned, rotatable, needle cylinders, a wrap spindle projecting through the upper cylinder, a wrapping head on said spindle positioned at wrapping level with respect to needles knitting in the lower cylinder, means for moving said spindle and said head into wrapping position eccentric of said cylinders and for moving said spindle and said head into an idle position substantially concentric of said cylinders, a heel and toe pocket spreader concentric with and rotatable by said wrap spindle and vertically movable independently thereof and means for causing said spreader to engage the heel or toe pocket of a stocking being knitted when said wrap spindle is in its idle, substantially, concentric position.

2. In a knitting machine having superposed, axially aligned, rotatable, needle cylinders, a wrap spindle, a wrapping head on said spindle positioned at wrapping level with respect to needles knitting in the lower cylinder, means for moving said spindle and head from an idle position substantially concentric with said cylinders to a wrapping position eccentric of said cylinders, a heel and toe pocket spreader concentric with said

spindle and said head, means for rotating said spindle and said spreader in unison with said cylinders and means for moving vertically said spreader independently of said rotating means.

- 6 3. In a knitting machine having superposed axially aligned needle cylinders, a wrap spindle eccentrically positioned with respect to the cylinders and having an integral head including a plurality of substantially identical flat fingers 10 all extending radially in the same horizontal plane from a common hub and being in close adjacency throughout the periphery of the head, each of said fingers having a radially tapered form being relatively narrow at the inner end 15 and wide at the outer end so that the adjacent sides of adjacent fingers are substantially parallel whereby selection of the desired fingers may be made by the breaking off of the remaining fingers at their narrow inner ends, and a yarn 20 eyelet in the outer end of each finger.

OSCAR FREGEOLLE.
